UNITED STATES PATENT OFFICE.

ISRAEL W. CUMMINGS, OF PHILADELPHIA, PENNSYLVANIA.

DESIGN FOR A GAME-BOARD.

SPECIFICATION forming part of Design No. 24,852, dated November 5, 1895.

Application filed October 23, 1894. Serial No. 526,762. Term of patent 7 years.

To all whom it may concern:

Be it known that I, ISRAEL W. CUMMINGS, a citizen of the United States, residing at Philadelphia, in the county of Philadelphia and State of Pennsylvania, have invented a new and original Design for Game-Boards, of which the following is a specification.

This invention relates to a new and original design for game-boards; and it has for its object to provide a design of this character that shall be both useful and ornamental.

The leading feature of the design resides in a game-board having a central rectangular portion divided into squares, a marginal portion directly encircling the outer rows of squares and consisting of corner squares, star-shaped figures arranged in the corner squares, and alternate oblong spaces and hour-glass-shaped figures arranged in a straight line between the corner squares.

A minor feature of the design resides in an ornamental border essentially consisting of a series of closely-arranged short parallel lines and a continuous series of small circular-shaped figures arranged on said lines.

The figure of the drawing is a plan view of a game-board embodying the herein-described design.

Referring to the drawing, the numeral 1 designates a game-board having a central rectangular portion 2, divided into rows of squares 3 and 4. Directly encircling the outer rows of squares the game-board is provided with a marginal portion consisting of corner squares 7, having therein star-shaped figures 35 and alternate oblong spaces 5 and hour-glass-shaped figures 6, arranged in a straight line between the corner squares. Surrounding the marginal portion described is an ornamental border essentially consisting of a series of 40 closely arranged short parallel lines and a continuous series of small circular-shaped figures arranged on said lines.

What I claim is—

The design for a game board herein shown 45 and described.

In testimony that I claim the foregoing as my own I have hereto affixed my signature in the presence of two witnesses.

ISRAEL W. CUMMINGS.
